Attorney.

UNITED STATES PATENT OFFICE.

EMORY E. ELLIS, OF ORANGE, MASSACHUSETTS, ASSIGNOR TO UNION CALIPER COMPANY, OF ORANGE, MASSACHUSETTS.

CALIPERS.

1,102,146.

Specification of Letters Patent. Patented June 30, 1914.

Application filed November 18, 1912. Serial No. 731,989.

To all whom it may concern:

Be it known that I, EMORY E. ELLIS, a citizen of the United States, residing at Orange, county of Franklin, Commonwealth 5 of Massachusetts, have invented certain new and useful Improvements in Calipers, of which the following is a specification.

This invention relates to measuring instruments and particularly to calipers of either the inside or the outside type, although the improvements are not necessarily restricted to calipers but may be used with good results upon dividers and similar instruments of precision.

15 Among calipers, as at present constructed, much difficulty has been found in using the calipers accurately upon an irregular surfaced object, such as a flanged hub or the like, where it is necessary to spring the legs 20 of the calipers over the flange to enable the calipers' points to engage the hub to determine its dimension.

The resetting of the points, after their expansion to pass an obstruction or their contraction to pass through a small opening, is as important as the initial caliper, hence the necessity of calipers which can be quickly set and re-set. The present invention, therefore has for its object to provide calipers 30 which will possess all the merits of the old style of calipers without being subject to the defects as noted above, and which may be used advantageously, either as inside or outside calipers, upon objects of an irregular 35 nature to secure their correct measurement.

In the accompanying drawing, in which similar numerals of reference denote corresponding parts in the several views thereof, I have illustrated a practical embodiment of 40 my invention, in which:

Figure 1 is a front view of a pair of calipers, and Fig. 2 is a section thereof on line 2-2 of Fig. 1.

Referring more particularly to the drawing, the numerals 3 and 4 denote a pair of calipers' legs, of any desired proportions or form, pivoted near their upper extremities on a fulcrum stud 5, and adapted for control by the compression bow spring 6. 45 One leg 3 of the calipers is provided at a suitable point with a transverse guide, or stop 7, so positioned as to limit the upward movement of the horizontal adjusting rod 8. This rod has an elongated slot 9 in which

the calipers' legs work. Said slot divides 55 the rod 8 into two spaced, parallel arms 10, suitably connected at their outer ends, exteriorly of the legs. Each arm has along its lower face a plurality of notches 11 adapted for selective engagement with a 60 locking pin 12 passing transversely through the leg 3 of the calipers, below the guide and stop pin 7. The rough adjustment of the calipers may thus be had by springing the legs over the object to be measured by exerting a pressure upon one or both of the legs. This will cause a movement of the adjusting rod relative to the legs and will permit the notches of said rod to engage the locking pin 12 on the leg 3, the stop pin 7 serving to 70 limit the upward movement of said rod.

The arms 10 are each formed with an elongated slot 13 in which fits a pin 14, passing through the leg 4 of the calipers and serving as a pivot for the adjusting rod. 75 This slot and pin connection permits a slight vertical and horizontal play of the adjusting rod 8.

The fine adjustment of the calipers is had through the elongated slot 13 and pin 14 80 which permit a movement of the adjusting rod proportionate to the length of the threaded adjusting screw 15, turned by a milled nut 16 and passing through one of the connecting end members of said pair of 85 arms 10.

The appliance is used in the well known manner, the rough adjustment being made by drawing the legs toward each other and engaging a pair of notches over the locking 90 pin. The fine adjustment is made by rotating the set screw and thus moving the rod.

In the event that the object to be measured is an irregular surface, such as a flanged hub, for example, over which flange 95 the legs must pass to engage the hub, the adjustment may be had by extending the legs to their maximum capacity to clear the flange and then they may be brought together over the hub and the dimension 100 measured, the relation of the locking pin and co-operating notches indicating the diameter. These notches may be numbered or graduated in any suitable manner if desired and when the measurement has been taken, the notches and pin are disengaged, and the legs again distended to clear the flange. The pin may then be reengaged with the coop-

erating notches, the position, or distinctive number of each having been taken when the measurement was made, thus determining the dimension desired, this construction 5 permitting the accurate resetting of the calipers to the exact hub dimension.

Various modifications coming within the spirit and scope of my invention, as defined in the appended claims, may be resorted to 10 whenever necessary.

I claim:

1. In a pair of calipers, caliper legs, a locking member on one of said legs, an adjustable member slotted to provide spaced 15 arms, said arms being notched for engagement over said locking member, a stop for limiting the upward movement of said adjustable member, the arms of said adjustable member having slots therein, a pin on one 20 of said caliper legs working in said slots,

and a screw to adjust said adjustable member relative to one of the legs.

2. In a pair of calipers, caliper legs and a locking member embracing said legs and having a combined pivotal and sliding connection with one leg and a selective locking 25 engagement with the other leg.

3. In a pair of calipers, caliper legs, and a locking member embracing said legs and having a pin and slot engagement with one 30 leg providing for a combined pivotal and sliding adjusting movement relative thereto and having a selective locking engagement with the other leg.

In testimony whereof I affix my signature 35 in presence of two witnesses.

EMORY E. ELLIS.
